UNITED STATES PATENT OFFICE.

SOLOMON A. LEHMAN, OF FORT WAYNE, INDIANA.

RACK FOR BATTERY PLATES.

Application filed June 26, 1925. Serial No. 39,659.

The invention relates to devices for supporting battery plates in acid containers during the process of manufacture.

In the manufacture of secondary battery plates it is essential to support the pasted grids in spaced relation in an acid bath during the charging operation. The support must be formed of a material that will not only insulate the grids but which will not be affected by the acids. A commonly used material is vulcanized rubber, but there is one disadvantage connected with the use of such material in that due to the heat generated by the electrical current the supports 10 bulge and the grids drop out.

The object of the invention is to provide a support in which battery plates may be treated while they are held in insulated spaced relation, the bulging of the insulating material being avoided.

Another object is to provide a portable support having the above described advantages by which a maximum number of plates may be inserted into and removed from 25 an acid bath, the acid being left in its container for rinse upon the plates disposed in another of the supports or in the same support, thus making a large saving in time.

The invention consists in a hollow rack 30 formed preferably of wood the sides being lined on their inner sides with vertically slotted insulating members having inwardly projecting flanges at the bottom of the slots for positively supporting the battery plates, 35 the end members being adapted to contact with the bottom of the acid container for spacing the sides of the support above said bottom and also forming means by which to carry the device.

An embodiment of the invention is illustrated in the accompanying drawings in which,

Figure 1 is a plan view of one exemplification of the support; Fig. 2 an end view of 45 the same; Fig. 3 a cross-section on line 3-3 of Fig. 1; Fig. 4 a cross-section on line 4-4 of Fig. 1.

In the illustrative embodiment of the invention the rack comprises an open top and bottom frame formed by two end members 50 1 and 2 and two side members 3 and 4, the said members being formed of some acid resisting material, preferably wood coated with paraffine. The end members are relatively high and hand holes 5 are formed therein

near their upper ends to facilitate the handling of the rack. The side and end members are secured together by the lead rods 6 that are inserted through alined apertures in the sides and the ends, the upper rods also being passed through the liners 7 that are disposed on the inner faces of the side members respectively. The ends of the rods 6 are split and the bifurcations are spread laterally into tight contact with the side members, thereby firmly securing the frame members together. The lower ends of the end members project below the sides so as to space the side members above the bottom of the tank or receptacle upon which the end members rest. 70

As shown in Figs. 2 and 3 the lower portion of each side member is thickened to provide a shoulder upon which the liner 7 rests. A groove 8 is formed in the top wall of this shoulder which preferably extends 75 from end to end of the side member and into which a depending flange or tongue 9 that is formed on the lower side of the liner is adapted to engage.

Each liner 7 is formed of insulating material preferably hard rubber. Vertical slots 10 are formed in the side of the liner facing the interior of the frame and at the base of the slots is a flange 11 which projects from the liner. The plates to be treated are inserted in the alined slots in the two liners, the opposite ends of their lower edges resting on the bases of the slots and upon the flanges, one such plate 12 being shown in Fig. 2. 90

Apertures 13 are formed at suitable intervals in the side members adjacent to the upper edge thereof and sockets 14 are formed in the liner in axial alinement with the apertures. Molten lead solidified as shown at 15 95 locks the liner to the side member. The liners are similar in all respects and they are similarly mounted on the side members.

In use the pasted grids are inserted in the alined slots 10 in the liners and the usual bus bars are attached to the grids in the usual manner; the rack is then deposited in the receptacle containing the acid and the electrical current is turned on. When the charging operation has been completed the 100 rack with the plates therein is lifted from the acid bath and another rack loaded with grids may then be inserted in the bath, thus saving much time in the operations. 105

The racks are economically built and they 110

are of long life. They positively support the plates at all times and all bulging of the sides is avoided.

What I claim is:

- 5 1. A portable battery-plate rack comprising a hollow frame having an open top and open bottom and also having its end walls projecting below the lower edges of its side walls, insulating members supported on the inner faces of the opposite side walls of the frame respectively, each said member having a plurality of vertical slots in its exposed vertical face, and a flange projecting laterally from said face of each member and adapted to be engaged by the lower edge of the battery plates disposed in the slots.
- 10 2. A battery-plate rack comprising a hollow frame formed of separate side and end walls releasably secured together, the end walls extending below the plane of the lower edge of the side walls, insulating members on the inner face of the opposite side walls of the frame respectively, each said member having a plurality of vertical slots in its exposed vertical face, a flange at the lower ends of the slots projecting laterally from said face of the insulating member adapted to be engaged by the lower edges of the plates that are disposed in the slots, and
- 15 30 means to lock the insulating members to the

said side walls of the frame and comprising a plurality of fusible members extending through the side walls and engaged to the insulating members.

3. A battery-plate rack comprising a wooden frame having two end members and two side members, the lower ends of the end members projecting below the side members, a shoulder formed on the inner side of each side member and extending from end to end thereof, each said shoulder having a longitudinal groove therein, an insulating member on each side member having a depending tongue thereon adapted to engage in said groove, a flange projecting inwardly from the exposed vertical face of each insulating member, said face of said member having a plurality of parallel vertical slots therein extending from the upper edge of said member to the plane of said flange, means projecting through the side members and engaging the insulating members to lock the upper portion of said insulating members to the side members, and means extended through the end members, the insulating members and the side members to secure the same together.

In witness whereof I have hereunto set my hand this 20th day of June, 1925.

SOLOMON A. LEHMAN.
